EXTENSIBLE BRACELET CLASP

John Dalo, Providence, R. I., assignor to A and Z Chain Company, Providence, R. I., a corporation of Rhode Island

Application August 30, 1935, Serial No. 38,594

7 Claims. (Cl. 24—71)

This invention relates to clasps and more particularly to extensible clasps for connecting the ends of watch-bracelets or the like.

One of the objects of the invention is to provide a clasp of the type indicated which may be manually contracted to adjust the length of the bracelet.

Another object of the invention is to provide a clasp of the type indicated which will yield to permit a limited expansion and contraction in its adjusted relationship to hold the bracelet snugly on the wrist of the wearer.

Another object of the invention is to provide a clasp of the type indicated including foldable members for extending the length of the bracelet, to permit it to be passed over the hand, and then collapsed to tighten the bracelet around the wrist.

Still another object of the invention is to provide a clasp of the type indicated which is neat and ornamental in appearance, of a compact and simple structure permitting economical manufacture and assembly, and one which is positive in its operation to latch the parts in adjusted relationship.

These and other objects will become more apparent from the following description of one form of the invention as illustrated in the accompanying drawing. It is to be understood, however, that the drawing is for purposes of illustration only and not a definition of the limits of the invention, reference being had for this purpose to the appended claims. In the drawing:

Fig. 1 is a plan view of a two-part bracelet connected by the extensible clasp forming the subject-matter of the present application;

Fig. 2 is a side elevational view of the clasp showing its pivoted sections in extended relationship and illustrating the manner in which the sections are folded into overlying relationship;

Fig. 3 is a bottom view of the clasp showing its sections in extended relationship;

Fig. 4 is a longitudinal sectional view of the clasp taken on line 4—4 of Fig. 2 and showing the means for latching the extensible slide in its innermost contracted relationship with respect to the foldable members;

Fig. 5 is a view similar to Fig. 4 showing the slide extended to its outermost position with its controlling spring compressed;

Fig. 6 is a transverse sectional view taken on line 6—6 of Fig. 1 and showing the projecting lug for releasing the latching means;

Fig. 7 is a view similar to Fig. 6 taken on line 7—7 of Fig. 1 and showing the spring for yield-

ingly holding the slide in adjusted relationship with respect to the foldable members;

Fig. 8 is a detail perspective view of the rack-bar mounted on the slide;

Fig. 9 is a detailed perspective view of the extensible slide; and

Fig. 10 is a detailed perspective view of the pawl for latching engagement with the rack-bar.

Referring now to Fig. 1 of the drawing, the clasp member 10 forming the subject-matter of 10 the present application is shown as connecting the ends of the sections 11 and 12 of a two-part bracelet. The bracelet sections as illustrated comprise a plurality of flexibly connected links having terminal connectors 13 at their outer ends 15 for attachment to the bails of a wrist-watch, not shown, but it is to be understood that any other prevailing mode of bracelet may be substituted, such as fabric, leather, mesh or the like and that the terminal connectors 13 may take other forms. 20

The preferred illustrated embodiment of the extensible clasp 10 is comprised of a plurality of foldable sections including a body member or housing 14, a pair of cooperating slidable members 15 and 16 forming a connecting link, and an end section 17. The body member or housing 14 is in the form of a plate 18, preferably of sheet-metal, curved longitudinally throughout its length to conform to the contour of the wrist. The plate 18 has opposite side portions 19 and 20 folded downwardly and inwardly with their edges 21 and 22 terminating in parallel spaced-apart relationship, see Figs. 6 and 7. The plate 18, together with the folded sides 19 and 20, provide longitudinally-extending channels 24 and 25 at 25 the opposite sides of the body member. At one end the plate portion 18 extends beyond the folded sides 19 and 20 and is bent to form a closed loop 26, while the opposite end of the plate portion 18 is rounded as at 27, see Fig. 1, to provide 30 a finger-piece for prying the clasp open. A pivot-pin 28 extends between the folded sides 19 and 20 of the plate 18 at the end of the body member 14 adjacent the finger-piece 27. 35

The member 15 forming one part of the connecting link is of rectangular shape with a centrally-depressed groove 32 extending throughout the greater portion of its length and forming side rails 33 and 34. The member 15 is pivotally connected to the body member 14 by a loop 35 at 40 its end embracing the pivot-pin 28 and the side rails 33 and 34 are adapted to slide in lateral channels 36 and 37 of usual construction in the link member 16. The relative sliding movement of the members 15 and 16 is limited by the en- 45

agement of a detent 38 on the member 16 with the opposite ends of the groove 32 in the member 15 into which the detent projects. At its outer end the member 16 is provided with a loop 40 for pivotal connection with the end section 17 of the clasp.

The end section 17 comprises a base plate 41 with its opposite sides 42 and 43 folded upwardly to provide projecting flanges. A pin 44 extends 10 between the side flanges 42 and 43 at one end of the section and is embraced by the loop 40 on the link member 16 for pivotal connection therewith. The width of the end section 17 is substantially equal to the spacing between the parallel 15 edges 21 and 22 of the body member or housing 14 and the flanges 42 and 43 on the section 17 have detents 45 for cooperation with these edges. The opposite end of the end section 17 has a 20 loop 46 for embracing the end link of the bracelet section 12 to provide a flexible connection therewith. As thus far described the clasp is not materially different from those heretofore used, the link members 15 and 16 being adapted to telescope one into the other and together with 25 the end section 17 to fold into the body member or housing 14 in overlying relationship in the manner shown by dash lines in Fig. 2; the link members and end section being curved throughout their length to conform to the longitudinal 30 curvature of the body member. As shown in Figs. 6 and 7, the link members 15 and 16 lie wholly between the flanges 42 and 43 on the end section 17 and the flanges lie wholly between the 35 terminal edges 21 and 22 of the folded sides of the body member 14. The folded sections are latched together by the engagement of the detents 45 on the side flanges 42 and 43 of the end section 17 with the edges 21 and 22 of the folded sides 19 and 20 of the body member 14. To maintain 40 the connecting link and end section properly positioned in the body member or housing 14 a projecting lug 47 formed on the link member 16 engages the plate 18.

The present invention is directed particularly 45 to the adjustable features of the clasp for manually contracting its length and for providing a resilient yielding action to permit limited expansion and contraction in its length when the parts are in adjusted relationship. To this end a slide 50 in the form of a hollow rectangular frame, shown in inverted position in Fig. 9, is mounted 50 in the body member 14 for relative longitudinal movement with respect thereto. The slide 50 is preferably formed by a plate of sheet-metal having its sides 51 and 52 folded downwardly and then inwardly to provide channels 53 and 54 adapted to nest in the channels 24 and 25 of the body member 14 with a close sliding fit. The central portion of the slide 50 is cut away between the channels 53 and 54 and throughout the greater portion of its length, thus forming cross-bars 55 and 56 at its opposite ends. The cross-bar 55 is flexibly connected to the end link of the bracelet section 11 by any suitable means such as the looped band 57 shown in Figs. 2 and 3. At the rearward end of the slide 50 adjacent the crossbar 56 the end of the folded side portion 51 is slotted in bifurcated form as shown in Fig. 9 and thereafter bent at right-angles toward the crossbar 56 to provide a bearing 58, see Fig. 4. At its forward end the folded bottom portion of the channel 54 is formed with a longitudinal slot 59.

One-way latching means are provided which 75 permit the slide 50 to be moved into contracted

relationship with respect to the body member 14 to adjust the length of the bracelet while acting to hold the slide in its adjusted position. The latching means includes a member 60 carried by the slide 50 and movable thereon to provide a 5 limited expansion and contraction of the clasp. Although the latching member 60 may be either a pawl or a toothed rack, in the present illustrated embodiment it is in the form of a rack-bar shown in detail in Fig. 8. The rack-bar 60 is mounted 10 for sliding movement in the channel 54 of the slide 50 by means of an extension rod 61 formed integrally therewith with its end projecting rearwardly through the bearing 58 and with a lug 62 at its forward end projecting through the slot 59. 15 The rack-bar 60 is provided with a series of teeth 63 which project inwardly toward the open center of the slide 50. Each of the teeth 63 has one side 64 inclined inwardly and forwardly toward the crossbar 55 and its opposite side 65 parallel with 20 the crossbar.

The rack-bar 60 is yieldingly held in a forward position with respect to the slide 50, as shown in Fig. 4, by a helical compression spring 66 surrounding the rod 61 and acting between an abutment 67 on the bar and the bearing 58 on the slide through which the rod extends. The forward movement of the rack-bar 60 with respect to the slide 50 is limited by the engagement of the lug 62 with the end of the slot 59 and the outward 30 movement of the slide 50 is limited by a lug 69 projecting inwardly from the abutment 67 on the rack-bar and engaging the bearing housing 26 at the forward end of the body member 14, see Fig. 5.

The latching means also includes a yielding pawl 70 shown in detail in Fig. 10 for cooperation with the teeth 63 on the rack-bar 60 to latch the slide 50 against outward movement with respect to the body member 14 while permitting the 40 parts to be contracted to adjust the length of the bracelet. The pawl 70 is in the form of an L-shaped spring having one end 71 rigidly fixed to the side wall 20 of the body member 14 and extending forwardly within the channel 53 in 45 the slide 50. The opposite end 72 of the leaf-spring is bent at substantially right-angles and extends through the hollow bearing 26 formed by the loop 26 at the forward end of the body member 14. The end 73 of the bent portion 72 which 50 cooperates with the teeth 63 on the rack-bar 60 has an angular face corresponding with the angle of the inclined side 64 of the teeth. The bent end portion 72 of the latching member 70 is provided with a forwardly-projecting lug 74 55 which extends through a slot 75 in the bearing 26 and upwardly to a position adjacent the top of the body member 14. The end of the lug is preferably serrated as at 76 to facilitate its engagement by the finger to move the pawl out of 60 engagement with the teeth 63 of the rack-bar 60 to release the slide 50. The mode of operation of 65 when complete clasp is as next explained.

With the foldable sections 14, 15, 16 and 17 of the clasp in extended relationship as illustrated in Figs 2 and 3 and with the slide 50 withdrawn from the housing 14 to the position shown in Fig. 5, the bracelet sections 11 and 12 connecting a watch or like article of jewelry are passed over the hand of the wearer. The clasp is then collapsed by first sliding the member 15 telescopically 70 into the member 16 and folding the sections 14, 16 and 17 in the manner illustrated in Fig. 2. The end section 17 is then pressed into the body member or housing 14 to cause the detents 45 to 75

5 snap by the spaced edges 21 and 22 to latch the parts in folded relationship. In this folded assembly the projecting lug 47 on the section 16 engages against the plate portion 18 of the body member 14, see Fig. 7. The lug 47 together with the pivot-pin 28 hold the intermediate link member 16 spaced from the plate 18 so that the slide 50 may move freely in the body member 14.

10 The slide 50 is then telescoped into the body member 14 to contract the clasp to adjust the length of the bracelet to conform to the wrist. The two parts are moved into contracted relationship by manually pressing the end of the slide 50 and the opposite end of the body member 14 15 between the fingers. During this inward movement of the slide 50 with respect to the body member 14 the latching end 73 of the yielding pawl 70 slides across the inclined sides of the teeth 63 on the rack-bar 60. The contraction of 20 the clasp is continued until the bracelet snugly fits the wrist at which time the straight side 65 of one of the teeth 63 on the rack-bar 60 is engaged by the correspondingly-shaped side of the end 73 of the pawl 70 to latch the rack-bar 60 25 in adjusted relationship with respect to the body member 14.

30 The slide 50 may then have a limited expansion and contraction to conform to the flexing of the wrist due to the yielding of the spring 66 which acts between the abutment 67 on the rack-bar 60 and the lug 58 on the slide 50. As the slide 50 is drawn out of the body member 14 it moves with respect to the rack-bar 60 against the compression of the spring 66 and has a range of movement as indicated in Fig. 5. When the slide 50 is released the spring 66 acts between the abutment 67 on the rack-bar 60 and the bearing lug 58 on the slide to draw the latter into the body member 14, this movement being limited by the 40 engagement of the lug 62 on the rack-bar with the end of the slot 59. In this manner the slide 50 is yieldable with respect to the rack-bar 60 and body member 14 to which it is latched to adapt the length of the bracelet to be automatically adjusted within definite limits.

45 When the bracelet is to be removed from the wrist the finger-nail is inserted under the lip 21 on the body member 14 to pry it away from the end section 17. The sections of the clasp may then be extended to the positions shown in Figs. 2 and 3 and the bracelet removed over the hand. When again applied to the wrist and collapsed the clasp will be properly adjusted to fit the wrist due to the latching engagement of the pawl 70 50 with the rack-bar 60. In other words, when once adjusted the clasp will retain its adjustment even though the folded sections are extended. If however, the bracelet is found to be too tight or for any other reason it is desired to extend the 55 length of the clasp the latching end 73 of the pawl 70 may be moved away from the teeth 63 on the rack-bar 60 to release the slide 50. To accomplish this result the serrated end 76 of the projecting lug 74 on the pawl is engaged by the 60 finger and slid to the right as viewed in Fig. 6. The slide 50 may then be freely withdrawn from the body member 14 having a range of adjustment from the position shown in Fig. 4 to that 65 shown in Fig. 5; the inwardly-directed lug 69 engaging the bearing 26 on the body member 14 to limit its outward movement. The length of the bracelet can then be readjusted in the manner as previously explained by moving the slide 50 into contracted relationship with the body member 14, this adjustment being permitted by the slid-

75 ing of the teeth on the rack-bar over the inclined end of the pawl. Although the sections of the clasp have been described as preferably made of sheet-metal folded or bent to shape, it is to be understood that they may be made of any other suitable material whether molded, pressed or otherwise formed. It is also to be understood that the clasp may be made without the foldable sections and including only the housing or body member 10 14 and the slide 50 and still be within the scope of the present invention.

15 Having now described the invention it will be observed that an improved clasp is provided having a simple and compact structure for yieldingly holding a bracelet in adjusted position. It will also be apparent that the clasp provides for manually contracting a pair of sliding members into 20 adjusted relationship while adapting them to be freely movable inwardly and automatically extended under the control of resilient means.

25 Although only one embodiment of the invention is herein shown and described it is noted that variations may be made in the form and arrangement of the parts within the spirit and scope of the invention. Therefore, without limiting myself in this respect, I claim:

30 1. An extensible clasp for bracelets comprising a plurality of foldable members, a slide on one of the foldable members having oppositely disposed channels at its sides, a ratchet means in one of the channels on the slide, a spring carried by the cooperating foldable member and lying in the channel at the opposite side of the slide, said spring being formed with a pawl to yieldingly 35 engage the ratchet, and means on the spring projecting from the end of the foldable member for releasing said spring from engagement with the ratchet to release the slide.

40 2. An extensible clasp for bracelets comprising a plurality of members adapted to be folded into overlying relationship with an opening therebetween, a slide between the folded members, a rack-bar on the slide and movable longitudinally thereof, a pawl having one end fixed to one of the 45 folded members and its opposite end yieldingly engaging the rack-bar, said pawl and rack-bar having inclined teeth for permitting the slide to be telescoped into the folded members, a spring between the rack-bar and slide for yieldingly 50 holding the latter in adjusted position, and a finger-grip on the pawl for manually moving it out of engagement with the rack-bar to release the slide.

55 3. An extensible clasp for bracelets comprising a plurality of members adapted to be folded into overlying relationship with an opening therebetween, a slide in the opening between the folded members for adjusting the length of the clasp, said slide having a channel at one side, a rack-bar 60 slidably mounted in the channel in the slide, a spring in the channel acting between the rack-bar and slide, and a latching member on one of the foldable members arranged to cooperate with the teeth on the rack-bar to hold the slide in 65 adjusted position with respect to the folded members.

70 4. In a device of the type indicated, a clasp member having inturned flanges at its sides to provide spaced channels, a slide in the clasp member having channels at its sides nested in the channels on the clasp member, a rack-bar in the channel at one side of the slide, guiding means in the channel for mounting the rack-bar for movement therein, a spring acting between the 75

- slide and the rack-bar, and a resilient pawl on the clasp member for cooperation with the rack-bar, the end of the pawl and the teeth on the rack-bar being formed to adapt their sides to slide past each other when the slide is moved into the clasp member and to latch against movement in the opposite direction, and a projection on the pawl for moving it away from the rack-bar to release the slide.
5. An extensible clasp for bracelets comprising a pair of members connected to slide relatively of each other, said members being adapted to connect the opposite ends of a bracelet, a toothed ratchet on one of the slideable members, a yielding pawl on the other member having an inclined portion adapted to slide past the teeth on the ratchet in one direction and to interlock therewith to prevent its movement in the opposite direction, and a spring connecting the ratchet and the member on which it is mounted to provide a limited relative movement therebetween.
10. 6. In an extensible clasp for bracelets comprising a pair of members connected to slide relatively of each other, said members being adapted to connect the opposite ends of a bracelet, a ratchet mounted on one of the sliding members and movable longitudinally thereof, a resilient pawl on the opposite member inclined with respect to the ratchet and engageable therewith, said pawl being adapted to slide along the ratchet as the members are slid into contracted relationship and interlocking to hold the members in adjusted relationship, a spring between the ratchet and member on which it is mounted, said spring adapted to yield to provide limited extension movement between the sliding members, and a finger grip on the pawl for manually releasing it from the ratchet.

pawl on the other member cooperating with the ratchet, said pawl being slideable along the ratchet as the members are slid into contracted relationship and interlocking to resist extension movement of the members, and a spring between the ratchet and member on which it is mounted adapted to yield to provide a limited relative movement therebetween.

7. An extensible clasp for bracelets comprising a pair of members connected to slide one with respect to the other, said members being adapted to connect the opposite ends of a bracelet, a ratchet mounted on one of the members and movable longitudinally thereof, a resilient pawl on the opposite member inclined with respect to the ratchet and engageable therewith, said pawl being adapted to slide along the ratchet as the members are slid into contracted relationship and interlocking to hold the members in adjusted relationship, a spring between the ratchet and member on which it is mounted, said spring adapted to yield to provide limited extension movement between the sliding members, and a finger grip on the pawl for manually releasing it from the ratchet.

JOHN DALO.
